UNITED STATES PATENT OFFICE.

LUCIA K. MATHEWS, OF SAN FRANCISCO, CALIFORNIA, ASSIGNOR TO PANAMA-PACIFIC INTERNATIONAL EXPOSITION CO., OF SAN FRANCISCO, CALIFORNIA, A CORPORATION OF CALIFORNIA.

DESIGN FOR A BADGE OR SIMILAR ARTICLE.

44,689.

Specification for Design.

Patented Sept. 23, 1913.

Application filed July 8, 1913. Serial No. 777,965. Term of patent 3½ years.

To all whom it may concern:

Be it known that I, LUCIA K. MATHEWS, a citizen of the United States, residing in the city and county of San Francisco and State of California, have invented a new, original, and ornamental Design for Badges or Similar Articles, of which the following is a specification, reference being had to the accompanying drawing, forming part thereof.

The figure is a plan view of the badge illustrating my new design.

I claim:

The ornamental design for a badge or similar article as shown.

LUCIA K. MATHEWS.

Witnesses:

THEODORE W. CHESTER,
C. F. ELDRIDGE.
